UNITED STATES PATENT OFFICE.

LOUIS RIESKE, OF MAYFIELD, OHIO, ASSIGNOR, BY DIRECT AND MESNE ASSIGNMENTS, TO SADIE M. MOORHOUSE, OF CLEVELAND, OHIO.

COMBINED HIGH AND LOW LEVEL VALVE AND DEPTH INDICATOR.

Application filed May 25, 1921. Serial No. 472,615.

To all whom it may concern:

Be it known that I, Louis Rieske, a citizen of the United States, and resident of Mayfield Village, in the county of Cuyahoga and State of Ohio, have invented certain new and useful Improvements in Combined High and Low Level Valves and Depth Indicators, of which I hereby declare the following to be a full, clear, and exact 10 description, such as will enable others skilled in the art to which it appertains to make and use the same.

The objects of the invention are to provide an improvement in a combined high 15 and low level valve and level indicating device for the gasoline supply leading to the carburetor of an explosion engine such as is employed to drive a motor car, and the invention is designed to notify the operator 20 of the car when the supply is getting low in plenty of time to enable him to call at a gas station and get the supply renewed.

The device is also constructed and arranged to provide a gauge by means of 25 which the level of the fuel in the main supply tank can always be ascertained.

The invention comprises, an independent vertical cylinder supplied with fuel oil from the main supply tank, and communicating 30 therewith, and provided with an inlet opening at the lower end connected by means of a supply pipe or passage with the lower end of said tank, the aforesaid openings in the cylinder and tank being at the 35 same level, said cylinder provided with two outlet openings at different levels, and with a float valve which normally closes the lower outlet, and remains closed until the flow of fuel ceases from the upper outlet, at which 40 time the float valve is manually liberated to permit the fuel oil to flow through the lower opening.

The level of the fuel oil will then be high 45 enough in the main tank to provide a sufficient amount of fuel, to run the motor car to the nearest town, or gasoline station, and, the remaining supply may consist of one or more gallons as desired.

The invention is hereinafter further described, shown in the accompanying drawings and specifically pointed out in the 50 claims.

In the accompanying drawings Fig. 1, is a vertical section showing the construction 55 of the various parts.

In this view A, is a vertical cylinder through which the supply of fuel oil passes from the main supply tank B, to the carburetor; C, is the supply pipe leading from the lower end of the main supply tank to 60 the lower part of the vertical cylinder A.

The pipe may be flexible if desired.

D, is the lower outlet opening leading from the auxiliary container at the same level as that of the supply pipe C. 65

This opening is normally closed by the float valve, E, which is provided with an elongated stem F, that protrudes through the movable cover G.

A cap H, pressed upon a tapered seat I, 70 retains the valve E, in position to close the lower outlet opening D. J, is a second outlet opening positioned at a higher level than the opening D.

The gasoline flows through this opening 75 until the supply thereof is exhausted in the main and auxiliary containers to the level of the lower edge of this opening. At this time a predetermined amount of gasoline will remain in the containers sufficient to 80 enable the operator to run the car a number of miles, or sufficient to enable him to reach a gasoline station.

The cap is then removed from the valve 85 stem and the float will rise thus permitting the gasoline to flow from the lower opening, D, until the containers are completely exhausted.

The level of the fuel oil will always remain the same in the cylinder and the container, and when it is desired to ascertain the level of the fuel oil in the main container, the cap is removed from the valve stem, which liberates the float, the elevation 90 of the float can then be easily read upon the valve stem which is preferably graduated for this purpose, this will indicate the level of the fuel oil and the amount remaining in the main container.

The valve stem is preferably constructed 100 of spring wire and a yielding part K, therein, makes it possible for the valve to adjust itself closely to its seat and also provides for a resilient pressure upon the valve, which is preferably composed of cork or soft 105 substance.

The device is most conveniently placed in front of the seat S, underneath which the tank B, is ordinarily concealed as in the Ford motor car, but may be placed in other 110

situation and passes upward through the floor T, and is attached thereto by means of the adjustable stop flange V, and screws on bolts W, W.

5 The cylinder A, is pushed up through an opening X, in the floor and the position of the stop flange determines the level of the fuel oil in the cylinder relatively to the level of the fuel oil in the tank, and the stop flange 10 should be so set that the inlet opening in the cylinder and the outlet opening in the tank should have the same level.

It also serves as a means for attaching the cylinder to the floor.

15 Having described the invention what I claim as new and desire to secure by Letters Patent is:

1. In a combined high and low level valve, and depth indicator, in combination with a 20 main fuel oil container, and a vertical cylinder supplied therefrom and closed at the bottom, the lower ends of said container and cylinder being in communication with each other, said cylinder provided with upper 25 and lower outlet openings, a float valve for said lower opening, and releasable means for securing said valve in place, said valve when released permitting the flow of fuel oil through said lower outlet opening, said 30 valve provided with a valve stem, a cover for said cylinder, said cover provided with an opening through which said valve stem is adapted to project when said valve is released, said valve stem comprising a depth 35 gauge, to indicate the fuel oil level in the main fuel oil container.

2. In a device for the purpose set forth, in combination with a main container, a 40 vertical cylinder having a closed bottom, a passage connecting the lower ends of said main container and vertical cylinder, outlet passages leading from said vertical cylinder,

at different levels, a float valve and stem therefor, said float valve adapted to close said lower outlet opening, a closure for the upper end of said cylinder, said closure provided with an opening, a stem for said valve, said stem passing through said opening in said closure, and a removable cover for said opening, said cover adapted to engage said valve stem and close said valve on its seat when said cover is put in place over said opening.

3. In a device for the purpose set forth, in combination, a vertical cylinder, an inlet opening adjacent to the lower end thereof, outlet openings arranged at different levels leading from said cylinder, a float valve controlling said lower outer opening, and a retaining means for said valve said retaining means vertically movable on said cylinder.

4. In a device for the purpose set forth, the combination with a main fuel oil container, and a vertical cylinder supplied therefrom and closed at the bottom, the lower ends of said container and cylinder being in communication with each other, said cylinder being provided with a central outlet opening, and with an outlet opening 65 in its side wall above said central opening, a valve for controlling said central opening, a cover for said cylinder, said cover provided with a central opening, a valve stem for said valve, guided in said central opening, and a vertically adjustable cover for said opening, said cover serving as a retaining means for said valve.

In testimony whereof, I hereunto set my hand this 21 day of May, 1921.

LOUIS RIESKE.

In presence of—

Wm. M. MONROE,
Sol W. WYMAN.
